UNITED STATES PATENT OFFICE.

JOHN T. WILCOX, OF LEOMINSTER, MASSACHUSETTS, ASSIGNOR TO ALBERT W. WILLIAMS AND GEORGE L. WINN, OF SAME PLACE.

DESIGN FOR A COMB.

SPECIFICATION forming part of Design No. 28,156, dated January 11, 1898.

Application filed December 8, 1897. Serial No. 661,210. Term of patent 3½ years.

To all whom it may concern:

Be it known that I, JOHN T. WILCOX, a citizen of the United States, residing at Leominster, in the county of Worcester and State of Massachusetts, have invented and produced a new and original Design for a Comb, of which the following is a specification, reference being had to the accompanying drawings, forming a part thereof.

- The leading feature of my design consists in the shape of the teeth of the comb, which teeth are arranged in groups, the teeth of adjacent groups being oppositely curved.

Figure 1 is a side elevation of the comb embodying my design, and Fig. 2 is a plan view of the same.

A represents the head of the comb, and B and B' groups of teeth extending from the head, the teeth in one group being curved in an opposite direction to the teeth in the next group. The teeth in addition to being curved are given a wave-like formation.

I claim—

The design for a comb herein shown and described.

JOHN T. WILCOX.
